ALARM FOR DEAF PERSONS

Pasquale Rody, Phoenix, Ariz.

Application January 23, 1951, Serial No. 207,351

3. Claims. (Cl. 161—22)

1

This invention relates to an alarm device operable in connection with a timepiece which is for use in arousing deaf persons from sleep. More particularly, it has to do with such alarm device in which vibrations imparted to the frame of a bed occupied by the deaf person cause such person to be aroused.

In my prior application, Serial No. 27,004, filed May 14, 1948, Alarm for Deaf Persons, now Patent No. 2,561,481 dated July 24, 1951, there is disclosed and claimed an alarm device which includes a vertically disposed electromagnet adapted to be positioned below and space from the rail of a bed and fixedly secured thereto, a vertically disposed armature connected to the electromagnet for vibratory movement toward and away from the bed rail, and a hammer projecting transversely of the armature adjacent the upper end thereof and engageable with the bed rail upon vibratory movement of the armature toward the bed rail.

It has been found that by replacing the vertically disposed electromagnet, the vertically disposed armature connected to the electromagnet, and the hammer projecting from the upper end of the armature, of the device of my application Serial No. 27,004, by a vertically disposed motor having the rotatable motor shaft projecting from the upper end thereof, the motor being provided with means for fixedly supporting it in side by side spaced relation with respect to and from the side rail of a bed frame, a horizontally disposed bar connected intermediate its ends to the projecting motor shaft for rotation with the latter, and a horizontally disposed resilient element arranged adjacent each end of the bar and having one end fixedly secured to the adjacent end of the bar and having the other end provided with means forcibly and slidably engageable with the adjacent face portion of the bed frame side rail upon rotary movement of the bar, an alarm device results which is especially efficient and positive in operation, and is commercially feasible.

In the accompanying drawings:

Figure 1 is an elevational view of the alarm device operable in connection with a timepiece according to the present invention applied to the side rail of a bed frame.

Figure 2 is an enlarged sectional view taken on the line 2—2 of Figure 1.

Figure 3 is a sectional view taken on the line 3—3 of Figure 2.

Figure 4 is a sectional view taken on the line 4—4 of Figure 2.

Figure 5 is an enlarged fragmentary elevational

2

view showing the connection of the housing and motor enclosing casing to a flanged side rail of a bed frame.

As shown in Figure 1, an electric clock 10, having contacts adapted to close an electrical circuit at a predetermined time, is connected to a convenience outlet 11 in a house wiring system by means of a conducting cord 12, and to the alarm device generally indicated by the numeral 13 by means of a conducting cord 14. The alarm device 13 is secured to the frame 15 of a bed 16 in such manner that vibrations produced by the alarm device will be conveyed by means of the bed frame 15 to the sleeper in the bed.

15. The clock 10 is provided with an off-on switch 17, an alarm setting knob 18, and alarm time-indicating hand 19. The back of the clock 10 is provided with a socket, not shown, which is connected to the alarm contacts within the clock and 20 into which the plug of the connecting cord 14 is inserted.

The alarm device 13, Figures 2 to 4 inclusive, comprises a casing 20 open at its top in which is fixedly mounted a vertically disposed motor 21, 25 the rotatable shaft 22 of the motor projecting through and beyond the open end of the casing. Superimposed upon and secured to the open top of the casing 20 is a housing 23 the bottom 24 of the housing 23 having an opening 25 for loosely receiving the projecting shaft 22. Positioned within the housing 23 adjacent the free end of the shaft 22 is a horizontally disposed bar 26, the bar being connected intermediate its ends to the shaft 22 for rotation with the latter. Arranged 30 adjacent the ends of the bar 26 are horizontally disposed resilient elements 27 and 28 respectively, one end of the elements 27 and 28 being fixedly secured to the adjacent ends 29 and 30 respectively of the bar 26 and the other end of the elements 35 being provided with means forcibly and slidably engageable with the adjacent face portion of the side rail 31 of the frame 15 of the bed 16, said means being rollers 32 and 33 respectively, each connected to the ends 29 and 30 of the elements 40 27 and 28 for rotation about a vertical axis. The rollers 32 and 33, upon rotation of the shaft 22, are in turn, projected through the open side 34 of the housing 23, and forcibly and slidably engage the adjacent face portion of the side rail 31 of the 45 frame 15 of the bed 16. The forcible engagement of the rollers 32 and 33 of the elements 27 and 28 causes vibrations in turn to be imparted to the side rail 31 of the bed frame 15, which vibrations are then conveyed to the person in the bed.

50 Slidably supported on the top 36 of the housing

23 is a bracket 35, the bracket being detachably connected to the top 36 of the housing by means of a threaded bolt 37 extending slidably through the top 36, a washer 38 surrounding the bolt 37, and a threaded wing nut 39 in threaded engagement with the bolt 37 and bearing against the washer 38. The bracket 35 rests upon the top of the side rail 31 of the bed frame 15 and has a depending flange 40 adjacent one end which bears against the inner face of the side rail 31 when the housing 23 and bracket 35 are fixedly supported in side by side spaced relation with respect to the side rail 31.

Where the side rail 41 of the bed frame 15 is provided with a ledge or outwardly projecting flange 42, Figure 5, a bracket 43 is employed in place of bracket 35 which has an inturned end or hook 44, the hook 44 embracing the ledge or flange 42.

It will be understood that when the plug of the conducting cord 12 is inserted in the convenience outlet 11 in a house wiring system and the plug of the conducting cord 14 is inserted in the socket in the back of the clock 10, the necessary current will be supplied to the clock and the alarm device 13 will also be operated whenever its circuit which is connected to the main circuit in the clock is closed by the contacts in the clock at the hour set by means of knob 18 provided the off-on switch 17 is set in the proper position.

I claim:

1. An alarm device comprising a vertically disposed motor adapted to be positioned in side by side spaced relation with respect to the side rail of a bed and fixedly supported from said side rail, a vertically disposed rotatable shaft projecting from the upper end of said motor, a horizontally disposed bar connected intermediate its ends to said shaft for rotation therewith, a horizontally disposed resilient element arranged adjacent each end of said bar and having one end fixedly secured to the adjacent end of said bar and having the other end provided with means forcibly and slidably engageable with the adjacent face portion of said side rail upon rotary movement of said bar, an alarm clock including a time switch, and circuit connecting means connected between said time switch and said motor for actuating said bar and resilient elements at a selected time determined by said time switch.

2. An alarm device comprising a vertically dis-

posed motor adapted to be positioned in side by side spaced relation with respect to the side rail of a bed and fixedly supported from said side rail, a vertically disposed rotatable shaft projecting from the upper end of said motor, a horizontally disposed bar connected intermediate its ends to said shaft for rotation therewith, a horizontally disposed resilient element arranged adjacent each end of said bar and having one end fixedly secured to the adjacent end of said bar and having the other end provided with means embodying a roller connected thereto for rotation about a vertical axis forcibly and slidably engageable with the adjacent face portion of said side rail upon rotary movement of said bar, an alarm clock including a time switch, and circuit connecting means connected between said time switch and said motor for actuating said bar and resilient elements at a selected time determined by said time switch.

3. An alarm device comprising a casing having an open top arranged in side by side spaced relation with respect to the side rail of a bed, a housing superimposed upon and secured to the open top of said casing, a bracket slidably and detachably connected to the top of said housing resting upon the top of said rail and having an end bearing against the latter, a vertically disposed rotatable shaft projecting from the upper end of said motor and extending into said housing, said housing having the side contiguous to said side rail open, a horizontally disposed bar connected intermediate its ends to said shaft for rotation therewith, a horizontally disposed resilient element arranged adjacent each end of said bar and having one end fixedly secured to the adjacent end of said bar and having the other end provided with means embodying a roller connected thereto for rotation about a vertical axis projectable through the open side of said housing and forcibly and slidably engageable with the adjacent face portion of said side rail upon rotary movement of said bar, an alarm clock including a time switch, and circuit connecting means connected between said time switch and said motor for actuating said bar and resilient elements at a selected time determined by said time switch.
